(57) **CLAIM**

The ornamental design for a manual razor, as shown and described.

DESCRIPTION

FIG. 1 is a perspective view of the manual razor showing our new design;

FIG. 2 is a greatly enlarged partial perspective view of the proximal end of the handle of the razor;

FIG. 3 is a bottom plan view of the razor;

FIG. 4 is a top plan view thereof;

FIG. 5 is a right side elevational view thereof;

FIG. 6 is a left side elevational view thereof;

FIG. 7 is a front elevational view thereof; and,

FIG. 8 is a rear elevational view thereof.

The proximal end of the razor handle is disclosed separately in FIG. 2 for convenience of illustration.
